CANDLE HOLDER AND CANDLE

Henry Fraternali, Dobbs Ferry, N. Y.

Application December 9, 1936, Serial No. 114,892

8 Claims. (Cl. 67—27)

This invention relates to wax candles and holders therefor especially candles designed for use in religious services.

A primary object is to provide a wax candle with a plurality of replaceable wicks.

Another object is to provide a wax candle that will burn evenly.

Another object is to provide a wax candle that will not drip on the side thereof.

Another object is to prevent draughts reaching the lighted end of the candle.

Still another object is to provide a device for holding a wax candle in balanced upright position.

A further object is to provide a device of this kind with means for automatically keeping the candle in operative position during its consumption.

Another object is to provide a holder of this kind with means for preventing accidental extinguishment of the flame.

A further object is to provide a device of this kind with means for ventilating the same.

Another object is to provide a device of this kind with means for keeping the wicks in waxed condition.

A still further object is to provide a device of this kind that is pleasing and ornamental in appearance and one that requires but a minimum of attention.

Other objects and advantages will be obvious from the description of the invention to follow taken in connection with the accompanying drawings in which—

Fig. 1 is a front view of my improved candle holder and candle.

Fig. 2 is an enlarged perspective detail view showing the candle and candle elevating mechanism.

Fig. 3 is a side view of an improved candle partly broken away.

Fig. 4 is a top plan view of the candle of Fig. 3.

Fig. 5 is a detail view of the candle elevating mechanism.

Fig. 6 is a plan view of a detail of the elevating mechanism.

Fig. 7 is a sectional view of the wick and wax supporting plate and Fig. 8 is a top plan view thereof.

Fig. 9 is a side view and Fig. 10 is a plan view of the wick mounting.

Fig. 11 is a sectional view of the upper part of the holder.

Fig. 12 is a top plan view of the glass enclosure.

Fig. 13 is a plan view of a modified form of wax and wick supporting device.

Fig. 14 is an assembly view of a further modified form of candle elevating mechanism.

Fig. 15 is a side view of a modified form of improved candle.

Referring to the drawings, the improved candle holder comprises a base 20, a cylindrical housing or standard 21, a dome 22 mounted on a glass tube 23 on top of the housing and a cross 24 on top of the dome. A slot 25 may be formed in the housing for inserting coin offerings which fall into a box or container 26 inside of the housing.

The housing 21 encloses a wickless wax candle 15 27 and mechanism for elevating the same. The form of candle illustrated in Figs. 2 and 3 consists of an elongated cylindrical wax body 21 formed with alternating grooves 28 and flange portions 29. The lower surface of the body is 20 formed with a wedge shaped protuberance 30. The upper end of the body is formed with a central tapered depression 31 and a circular groove 32 near the peripheral edge.

The mechanism for elevating the candle consists of a cylindrical elevator member 33, either hollow or solid, made of suitable light material, such as aluminum or wood or the like, in the upper surface of which member is formed a wedge shaped depression 34. is a cork member 48 and supported by this cork and extending radially therefrom and there-around are a number of metal arms 49. Supported in a depressed portion of each arm having spring fingers 50 is a wick or taper 51, which wick protrudes slightly above the arm. The portion of the arm supporting the wick 51 is positioned directly over the grooved portion 46 of the disk. When the candle 27 is in position in its housing, the upper end thereof abuts against the disk 43 so that the cup 44 fits in the tapered depression 31 in the upper surface of the candle, and the disk grooved portions 46 fit in the circular groove 32 of the candle.

15 Embedded in cement in a groove in the inner flange 40 is a glass ring 52.

20 Removably mounted on the dome 39 of the housing 21 and seated in shoulder 41 in the surface thereof is a glass enclosure 53. This enclosure has an open bottom portion and a closed top portion 54 of glass and metal. Around the peripheral edge of the top portion are a plurality of spaced openings 55 and around the bottom are spaced openings 56. In the center of the top is 25 an opening 57. This glass may be colored red or any other desired color. When in position on the upper edge of the housing the glass enclosure surrounds the arms 49 with their wicks 51. Removably seated on the top portion of the glass 30 enclosure over the opening 57 is a glass chimney 58.

35 The glass tube 23 is mounted on the outer shoulder 42 of the dome portion 39. This tube is provided with openings 59.

40 In use, the candle 27 is placed on its seat on the elevator 33 through a door in the housing (not shown) and allowed to rise until its upper end abuts against the disk 43. The springs 36 normally press the elevator upward to keep the candle in abutting relationship with the disk. The wicks 51 which are over the grooves in the 45 disk are lighted. Three flames are illustrated to represent the Trinity. The flames from these wicks are visible through the glass enclosure 53 and tube 23. The necessary air for the flames passes through the openings 59 in the glass tube 23 and the openings 56 in the glass enclosure 53. The glass tube and enclosure however protect the flames against direct drafts thus preventing their 50 accidental extinguishment, and also allowing the flames to burn evenly. The heat from the flames melts the top of the candle and the wax oozes through the openings 45 and 47 into the cup 44 and grooves 46 submerging the cork and arms 49, keeping the wicks properly waxed. The cork 55 48 floats on the melted wax in the cup 44 permitting it to move up and down or around carrying the arms 49 around in an arcuate direction in the grooved portions 46. The glass ring 52 prevents the melted wax from spilling over.

60 Fig. 14 illustrates another form of candle elevating mechanism in which the candle 27 is supported on a platform 76. The platform is connected at four points to a flexible member or cord 77. This flexible member passes around pulleys 83 and is fastened to a weight 78 which tends to pull down the flexible member and thereby elevate the platform and candle. The weight is movable in a receptacle 79 which contains mercury 80. This mercury varies the effective weight of the weight 78 as the candle burns, thus preventing quick downward movement of said weight.

65 The form of improved candle shown in Fig. 15 is similar to that shown in Fig. 3 excepting that

there is a single continuous spiral flange 81 instead of a plurality of flanges.

70 As shown in Fig. 13, the disk for supporting the wick mounting may be formed with three spaced depressions 82 instead of the elongated grooved portions 46.

75 The weight 78 shown in Fig. 14 might take the form of a collapsible weight divided into a plurality of collapsible sections which would successively engage the support and prevent quick downward movement. In this case the weight would not move in a liquid.

I claim:

1. In combination, an elongated wax candle, a disk resting on the top of said candle and having 15 depressed portions for holding wax, a plurality of wicks floatingly supported in said depressed portions by said disk in engagement with the wax and mechanism for holding the candle and disk in abutting relationship.

20 2. In combination, an elongated wax candle, a disk resting on top of said candle and having depressed portions for holding wax, a plurality of wicks floatingly supported in said depressed portions by said disk in engagement with the wax 25 and mechanism for holding the candle and disk in abutting relationship, said mechanism including a spring motor and a member adapted to be moved by said motor into engagement with the candle.

30 3. In combination, an elongated wax candle, a disk resting on top of said candle and having depressed portions for holding wax, a plurality of wicks floatingly supported in said depressed portions by said disk in engagement with the wax 35 and mechanism for holding the candle and disk in abutting relationship, said mechanism including a plurality of spiral springs and a member adapted to be moved by said springs into engagement with the candle.

40 4. In a device of the kind described, in combination, a housing, a wickless wax candle therein, a wax holding disk, a plurality of wicks supported by said disk in engagement with the wax, a glass enclosure for said wicks, mechanism for holding the candle and disk in abutting relationship and means associated with the glass enclosure for discharging the air in the enclosure.

45 5. In a device of the kind described, in combination, a housing, a wickless wax candle therein, a wax holding disk, a plurality of wicks supported by said disk in engagement with the wax, a glass enclosure for said wicks provided with a central opening, mechanism for holding the candle and disk in abutting relationship and a 50 glass chimney over said central opening.

55 6. In a candle holder, a housing, a wax candle therein, a movable platform supporting said candle, mechanism for moving said platform, a disk abutting one end of said candle, said disk having a perforated cup portion and perforated grooved portions adapted to receive melted wax, a cork member in said cup portion, radial arms carried by said cork and extending into said grooved portions and a wick member carried by 60 each radial arm.

65 7. In a candle holder, a housing, a wax candle therein, a movable platform supporting said candle, mechanism including a plurality of springs for moving said platform, a disk abutting 70 one end of said candle, said disk having a perforated cup portion and perforated grooved portions adapted to receive melted wax, a cork member in said cup portion, radial arms carried by said cork and extending into said grooved por- 75

tions, a wick member carried by each radial arm, a glass ring surrounding said disk, a glass enclosure having openings in its side and a central opening and a chimney on said glass enclosure in communication with said central opening.

5 8. In a candle holder, a housing, a wax candle therein, a movable platform supporting said candle, mechanism including a plurality of springs for moving said platform, a disk abutting one end of said candle, said disk having a perforated cup portion and perforated grooved portions adapted to receive melted wax, a cork member in said cup portion, radial arms carried by

said cork and extending into said grooved portions, a wick member carried by each radial arm, a glass ring surrounding said disk, a glass enclosure surrounding said glass ring, said glass enclosure having openings in its side and a central opening, a chimney on said glass enclosure in communication with said central opening, an upright member on the upper end of the housing, a dome supported on said upright member and an ornament on said dome, said chimney, dome and ornament having communication with the atmosphere.

10 HENRY FRATERNALI.
